UNITED STATES PATENT OFFICE.

HERBERT AUSTIN, OF BROMSGROVE, ENGLAND.

WHEEL-RIM FOR HOLDING PNEUMATIC TIRES.

1,132,898.

Specification of Letters Patent. Patented Mar. 23, 1915.

Application filed February 28, 1912. Serial No. 679,821.

To all whom it may concern:

Be it known that I, HERBERT AUSTIN, a subject of the King of Great Britain, and residing at Bromsgrove, in the county of Worcester, England, engineer, have invented certain new and useful Improvements in Wheel-Rims for Holding Pneumatic Tires, of which the following is a specification.

According to a type of wheel rim which has been used for holding a pneumatic tire, a detachable ring, for use in holding one edge of the sheath of the pneumatic tire in place, has been slipped on around the sole-plate of the rim. This ring has been held 10 from slipping back, under the pressure tending to force it outward when the tire has been inflated, by a steel ring, split at one side, which has been sprung into a groove formed around the sole-plate of the rim. 15 The split ring projects from the groove and forms an abutment against which the first-mentioned ring is forced by the inflation of the tire. There is some liability of moisture and dirt getting in between the two rings 20 and working their way into contact with the pneumatic tube; and there is some liability that in opening out the abutment ring, in removing it from the groove, a permanent set will be given to it which will prevent it 25 holding itself by an elastic grip around the bottom of the groove, when placed therein.

Now, with a view to obviate the inconveniences referred to, a packing ring or length of rubber, or of other suitable soft 30 packing material, and conveniently of a round section, is substituted for the split ring above described, substantially half of it being let into a groove of the sole-plate of the rim which is of suitable cross-section to 35 receive it for the purpose required, and the outer lower corner of the ring which is slipped over the sole-plate is shaped in cross-section to bed snugly against the projecting portion of the packing. The packing, if in 40 the form of an extensible ring, may be readily stretched sufficiently to enable it to be removed from its groove and replaced therein, and whether in the form of a ring or a length of which the ends are brought 45 around together, makes a thoroughly water and dirt tight joint between itself and its groove and between itself and the ring which is slipped over the sole-plate of the rim. This packing may be strengthened by 50 a core of canvas or the like, or may have a wire embedded therein which, when the

packing is made as a ring, may be discontinuous for such a distance as will enable the ring to be conveniently stretched sufficiently to enable it to be removed from its 60 groove and replaced therein; or the ring may have a non-extensible but flexible core surrounded with packing material, in which case the groove may be of such depth as to allow the ring to be put in place therein, 65 after which its axis would be brought to coincide with the axis of the wheel and the ring would then be moved outward into a seating formed therefor in the outer side of the groove. 70

The ring which is slipped over the sole-plate of the rim may be adapted either to engage with a beaded or thickened edge of the sheath in the manner in which a beaded or thickened edge of a sheath is commonly 75 engaged by a turned-over edge of a rim, thereby securely holding it both from giving sideways or expanding circumferentially as the tire is inflated, or may be adapted to press sideways only against a wired edge of 80 a sheath to prevent such edge from giving out sideways while the tire is being inflated, the wiring preventing it from expanding circumferentially under the inflation. 70

In order that the invention may be clearly 85 understood, I will now describe practical applications of the same which are illustrated, by way of example, by the drawings herewith, of which:—

Figure 1 is a transverse section through 90 the tire sheath and wheel rim, in a case in which the edges of the sheath are unwired. Fig. 2 is a corresponding view to Fig. 1 showing a sheath with wired edges, and Fig. 3 is a section through the rim and the 95 packing ring in the case of a ring having a flexible but non-extensible core.

Referring first to the application of the invention shown by Fig. 1, the sheath A is of any ordinary or convenient character, 100 having thickened edges *a* one of which fits under a turned-over edge *b* of the rim B and the other of which fits under a corresponding portion *c* of a ring C which is adapted to be slipped over the sole-plate *b'* 105 of the rim. A groove *b'* is formed within the periphery of the sole-plate *b'* close to the outer edge thereof, and, after the ring C has been pushed sufficiently across the sole-plate of the rim to admit thereof, a 110 packing *d*, of soft jointing material which is conveniently in the form of a ring, is insert-

ed within the groove b^2 leaving substantially half thereof standing out from the groove. The ring C is formed, as seen in section, with a hollow c' which, as such ring is 5 pressed outward by the inflation of the tire, beds against the portion of the packing d which stands outward from the groove b^2 and thus insures a thoroughly moisture and dirt tight joint between the rim and the 10 ring C. A tool is shown in this figure for use in forcing the ring C inward after the tire has been deflated, or sufficiently so to permit thereof, for the purpose of removing the packing d from the groove b^2 and 15 allowing the ring C to be removed from the rim so that the tire can be removed from around the wheel. This tool comprises a yoke E which engages, as shown, with the rim at one side thereof, and passes over the 20 tire to a pivot connection e with a two-armed lever of which one arm f may be forced at its free end, by turning the other arm f' , against the ring C in a direction to force such ring in as required. A single tool may 25 be used for forcing the ring C inward at different points in succession around its circumference, or two or more of such tools may be employed for simultaneously forcing the ring in at different points.

30 Referring now to the application of the invention shown by Fig. 2, the wires g which are inserted in the edges of the sheath A insure that such edges can not elongate, and it is therefore necessary simply to prevent these edges moving sidewise under the 35 inflation of the tire. The side b^3 of the rim B forms simply an outward flange around the sole-plate b' of the rim, against which a flat side of the corresponding edge of the 40 sheath abuts, and the ring C is formed with a flat side c^2 to form an abutment for a flat side of the corresponding edge of the sheath, but it is preferred to form the inner edge of 45 this flat side c^2 with an inward rounded projection c^3 which presses somewhat into the material of the edge of the sheath and gives additional security against the entrance of moisture and dirt into the tire. Except for 50 these features, this form of the invention is the same as that described with reference to Fig. 1.

Referring now to the modification of the invention shown by Fig. 3, the groove b^2 is shown to be of considerable depth and the 55 packing ring d , of soft jointing material which has a flexible but non-extensible core d' , is first passed down into the bottom of the groove at one part of the circumference of the wheel, as shown, and can then be 60 passed around over the edge of the groove throughout the remaining portion of the circumference of the wheel. The ring is then moved so as to be central with the wheel and moved outward against a curved 65 seat b^3 in the outer side of the groove, as

indicated by broken line circle. The packing ring is maintained in this position by the outward pressure of the ring C, shown by broken lines, due to the inflation of the tire. It will be obvious that, for convenience 70 of manipulation, the rim should, in each case, be used so that the ring C shall be on the outer side of the wheel. In order to insure, in each case, against any risk of the packing d being forced out from the groove 75 b^2 by the outward pressure thereagainst of the ring C, and incidentally to give increased security against moisture and dirt getting in between the ring C and the packing, the ring C is formed to fit around a 80 portion of the outer side of the packing when the packing is within the hollow of the ring C. The packing will yield sufficiently, as the ring C is forced back under the inflation of the tire, to allow the outer 85 edge of the hollow of the ring C to pass over the portion of the packing which projects farthest from the groove b^2 .

Having fully described my invention, what I claim and desire to secure by Letters 90 Patent, is:—

1. In a wheel rim for holding a pneumatic tire, a sole-plate, an abutment at one side of the sole-plate for supporting one side of the pneumatic tire, a ring which may be slipped over the sole-plate at the other side of the pneumatic tire, a groove running around the outer surface of the sole-plate at the side thereof over which the ring is slipped, and an endless packing of elastic 95 waterproof jointing material which is partly within the groove and partly projects therefrom and against the projecting portion of which the ring is pressed by the inflation of the tire, whereby the said packing acts as an 100 abutment for one side of the tire and prevents moisture and dirt from getting in between the rim and tire.

2. In a wheel rim for holding a pneumatic tire, a sole-plate, an abutment at one 110 side of the sole-plate for supporting one side of the pneumatic tire, a ring which may be slipped over the sole-plate at the other side of the pneumatic tire, a groove running around the outer surface of the sole-plate at the side thereof over which the ring is slipped, and a continuous packing ring of elastic waterproof material which may be stretched to pass it over the sole-plate and then allowed to contract to tighten itself 115 within the groove leaving a portion thereof projecting from the groove which resists the outward thrust of the first-mentioned ring.

3. In a wheel rim for holding a pneumatic tire, a sole-plate, an abutment at one 125 side of the sole-plate for supporting one side of the pneumatic tire, a ring which may be slipped over the sole-plate at the other side of the pneumatic tire, a groove running around the outer surface of the sole-plate at 130

the side thereof over which the ring is slipped, and an endless packing of waterproof elastic material which is within the groove and partly projects therefrom, the 5 projecting portion resisting the outward thrust of the ring and the said projecting portion of the packing formed with a rounded surface as seen in transverse section, and the ring formed with a hollowed surface, to 10 bear against the packing, which is shaped to pass over the portion of greatest projection of the packing and fit around a portion of the outer side thereof.

4. In a wheel rim for holding a pneumatic tire, a sole-plate, an abutment at one side of the sole-plate for supporting one side of the pneumatic tire, a ring which may be slipped over the sole-plate at the other side 15 of the pneumatic tire, a groove running around the outer surface of the sole-plate at the side thereof over which the ring is slipped, a seat in the outer side of the groove the inner edge of which is farther from the 20

axis of the wheel than is the bottom of the groove, and a packing ring having a surface 25 of elastic waterproof material and a non-extensible core, said groove being of such depth that the packing ring can be first passed down into the bottom thereof at one part of the circumference of the rim and 30 then be passed over the edge of the rim throughout the remaining portion of the circumference thereof and then be brought into position concentric with the rim and with a portion of the packing projecting beyond 35 the rim around the entire circumference thereof, the packing then resisting the outward thrust of such first-mentioned ring.

In witness whereof I have hereunto signed my name this 14th day of February 1912, 40 in the presence of two subscribing witnesses.

HERBERT AUSTIN.
